JOHN HAYS HAMMOND, JR., OF GLOUCESTER, MASSACHUSETTS.

ELECTRIC-WAVE-RELAYING SYSTEM.

1,313,860.

Specification of Letters Patent.

Patented Aug. 19, 1919.

Application filed June 12, 1912. Serial No. 703,219.

To all whom it may concern:

Be it known that I, JOHN HAYS HAMMOND, Jr., a citizen of the United States, residing at Gloucester, in the State of Massachusetts, have invented certain new and useful Improvements in Electric-Wave-Relaying Systems, of which the following is a specification.

My invention relates to systems for the relaying of electric wave signals, and relates more particularly to the automatic reception and transmission of radio telegraph and telephone messages at a relay station, and relates furthermore to methods and apparatus for securing selectivity in such electric wave relaying systems.

In the accompanying figures:

Figure 1 shows a transmitting station on my selective electric wave relaying system. Fig. 2 shows a relay station on my system.

Fig. 3 shows a receiving station on my system, which is out of range of the transmitting station of Fig. 1, but within range of the relay station of Fig. 2.

Fig. 4 shows a relay station on my system, in which part of the apparatus is of a modified form, and which has also apparatus for the local amplification of the received signals.

In Fig. 1 an alternating current generator G, of a frequency preferably above the range of audibility, energizes the field coils F of a high-frequency alternator H. Alternator H is inductively coupled to the antenna A by means of the coils L and L¹. Antenna A is in circuit with a condenser transmitter N M, and interrupter I and a key K, and is grounded at E. A resistance microphone T, in connection with the battery B and electro-magnet D, controls the diaphragm M of the condenser transmitter.

The high-frequency alternator H produces oscillations in the antenna A and the generator G produces amplitude variations at a definite rate in these oscillations, and hence in the electric waves radiated from the antenna. The interrupter I has a definite rate, within the limits of audibility, and is operated in connection with the key K when telegraph signals are to be sent. When telephone messages are to be sent, the interrupter I and the key K are kept closed, and the sound waves at microphone transmitter T cause variations in the current through electromagnet D, which latter actu-

ates the diaphragm M, composed of iron or other magnetic substance, and the telephonic vibrations are impressed upon the antenna A by means of the variations in the capacity of the condenser transmitter M N, and hence upon the electric waves radiated therefrom.

In Fig. 2 receiving apparatus and transmitting apparatus are connected to the same antenna A¹. At the receiving side, antenna A¹ is in circuit with the inductance coil L² and the variable condenser C, and is grounded at E¹. The closed oscillatory circuit L³ C¹ is coupled to the open antenna circuit by means of the coils L² and L³, and both these circuits are in resonance with the high-frequency alternator H, of Fig. 1. By the action of rectifier R and coupling coils L⁴ and L⁵, circuit L³ C¹ supplies unidirectional current impulses to the circuit containing coil L⁶, condenser C², electromagnet D¹ and receiving telephone P, which circuit is in resonance with the alternating-current generator G of Fig. 1. Telephone P will enable telephone messages originating at T in Fig. 1 to be heard at the relay station. Electromagnet D¹ actuates the condenser transmitter M¹ N¹, which is in the transmitting antenna circuit A¹ L⁷ M¹ N¹ E¹. An alternating current generator G¹, which is of a frequency preferably above the limits of audibility, energizes the field winding F¹ of high-frequency alternator H¹. The frequency of generators G and G¹, and of alternators H and H¹ should be different. G¹ impresses periodic amplitude variations on the current of H¹, H¹ being inductively connected with the transmitting antenna circuit by means of the coupling coils L⁸ and L⁷. The electric waves radiated from antenna A¹ have periodic amplitude variations of a frequency above the limits of audibility, due to the action of generator G¹, and, in addition, vibrations are impressed upon the antenna circuit by means of the condenser transmitter M¹ N¹, which reproduces exactly the telephone messages, originating at transmitter T of Fig. 1, or the telegraph signals originating at key K and interrupter I of Fig. 1. These relayed signals or messages are thus sent out with renewed power from the relay station.

In Fig. 3 the receiving antenna A² is in circuit with inductance coil L⁹ and condenser C³ and is grounded at E². It is inductively coupled to closed oscillatory circuit L¹⁰ C³, and both these circuits are in

resonance with alternator H^1 of Fig. 2. The circuit $L^9 C^8$, by means of rectifier R^1 and coil L^{10} , supplies energy to the circuit $L^{11} C^4 P^1$, containing the coil L^{11} , condenser C^4 5 and receiving telephone P^1 , and being in resonance with generator G^1 of Fig. 2. All variations of the condenser transmitter $M^1 N^1$ of Fig. 2 will therefore be reproduced at telephone receiver P^1 , and hence the telephone messages originating at transmitter T of Fig. 1, and the telegraph signals originating at key K and interrupter I of Fig. 10 will all be received at P^1 of the receiving station in Fig. 3.

15 In Fig. 4, which is a modified form of relay station on my system, the receiving antenna circuit $A^3 L^{18} C^6 E^3$ is inductively coupled to the closed oscillatory circuit $L^7 C^7$, and both these circuits are in resonance 20 with the wave frequency of the transmitting station. By means of the rectifier R^3 and coupling coil L^{18} , circuit $L^{18} C^8 D^2$, which is in resonance with the periodic amplitude variations of the transmitted electric waves, 25 is energized. Electromagnet D^2 actuates the magnetic diaphragm S of the resistance microphone T^1 . T^1 is in circuit with battery B^1 and the electromagnets D^3 , D^4 , D^5 , D^6 , D^7 and D^8 . These electromagnets actuate, respectively, the magnetic diaphragms M^3 , M^4 , M^5 , M^6 , M^7 and M^8 , of a multiple condenser transmitter, which transmitter is in the transmitting antenna circuit $A^3 L^{21}$ 30 $L^{22} M^5 M^4 M^3 M^6 M^7 M^8 E^3$. An alternating current generator G^2 , of a frequency preferably above the limits of audibility, energizes the field winding F^2 of the high-frequency alternator H^2 . G^2 impresses periodic amplitude variations upon the current 35 of H^2 , H^2 being inductively connected with the transmitting antenna A^3 by means of the coupling coils L^{20} and L^{21} . The electric waves radiated from the antenna A^3 have periodic amplitude variations, of a frequency 40 above the limits of audibility, owing to the action of the generator G^2 , and, in addition, vibrations are impressed upon the antenna circuit, by means of the multiple condenser transmitter $M^3 M^4 M^5 M^6 M^7 M^8$, 45 which reproduces, with an amplified volume, the telephone and telegraph messages originating at the transmitting station. These messages are thus sent out with increased 50 power from the relay station. This multiple condenser transmitter has already been 55 fully described in another application of mine, (Serial No. 702,175, filed June 7, 1912), and so need not be described in greater detail here.

60 This multiple condenser transmitter can also be used to produce an amplification of sounds or other signals at the relay station or elsewhere. As shown, it is inductively coupled, by means of the coil L^{22} , with the 65 circuit containing the coil L^{23} , rectifier R^4 ,

loud-speaking telephone Q and electromagnet D^9 , and the amplified currents induced in this latter circuit will produce amplified sounds at Q , or will operate through the electromagnet D^9 and relay switch W to actuate local mechanisms $U V$. 70

Other means may be employed for reproducing amplitude variations or group frequencies in my electric waves, such as revolving coils, high-frequency interrupters 75 and the like, shown and described in other applications of mine, other forms of microphones and other transmitters may be used at my transmitting and my relay stations, and various other changes and modifications, 80 within the ability of those skilled in the art, may be made in the particular apparatus shown and described herein, without departing from the spirit of my invention, provided the means set forth in the following claims be employed.

I claim as my invention:—

1. A system comprising a sending station adapted to emit electric waves having definite characteristics, a receiving station, and a relaying station, interposed between the sending station and the receiving station, provided with means for emitting waves of different definite characteristics and means for receiving variable wave characteristics produced at the sending station and impressing identical variations on the waves emitted from said relay station, said receiving station being turned to the wave characteristics of the relay station. 95

2. A system for the relaying of wireless signals, which comprises a sending station emitting electric waves having a fixed characteristic and a variable characteristic, a receiving station, and a relay station provided with means for receiving and emitting electric waves of different fixed characteristics and the same variable characteristic. 100

3. In a system for the relaying of wireless signals, a relay station comprising doubly selective receiving means, independent means for emitting waves having predetermined lengths and predetermined amplitude variations and automatically actuated means controlled by said receiving means for impressing variations on the emitted waves. 110

4. A method for relaying radio messages, which consists in transmitting waves having fixed characteristics and a variable characteristic from a transmitting station, receiving said waves at a relay station, automatically emitting waves from said relay station having different fixed characteristics from and the same variable characteristic 120 as the first-mentioned waves, and receiving the last-mentioned waves at a receiving station. 125

5. In a system for the relaying of radio messages, a relay station comprising means 130

for receiving electric waves having predetermined characteristics, independent means for emitting electric waves having different predetermined characteristics, and 5 means actuated by the received waves for impressing variations on the emitted waves.

6. A relay station for radio telephony, comprising means for receiving electric waves having fixed characteristics and a 10 variable characteristic, means for emitting waves having different fixed characteristics, and automatic means for impressing the variable characteristic of the received waves upon the emitted waves.

15 7. A relay station for radio signals, comprising means for receiving tuned electric waves with periodic amplitude variations, means for amplifying the received signals, means for transmitting differently tuned 20 electric waves with different periodic amplitude variations, means for impressing the amplified signals upon the last-mentioned waves, and means for receiving the signals locally in an amplified form.

25 8. A relay station for radio telephony, comprising selective means for receiving electric waves having telephonic variations, selective means for emitting electric waves, automatic means for amplifying the telephonic variations and impressing them upon the emitted waves, and means for amplifying the received telephone messages.

35 9. A method of relaying in radio telephony which consists in transmitting waves having a plurality of characteristics, impressing telephonic variations upon said waves, receiving said waves at a relay station, automatically emitting waves from said 40 relay station having different characteristics from the first-mentioned waves but the same telephonic variations, and receiving the last-mentioned waves at a receiving station.

10. The combination with transmission 45 means including means for generating electrical oscillations of a predetermined frequency, means for simultaneously impressing regular periodic variations of a predetermined frequency and irregular undulations corresponding to sound waves upon said oscillations of a relay including receiving means comprising responsive means in resonance with said oscillations, responsive means controlled by said first 50 mentioned responsive means and in resonance with said periodic variations, means for generating electrical oscillations of a predetermined frequency, means for impressing regular periodic amplitude variations of a predetermined frequency upon said last mentioned oscillations, and means controlled by said second mentioned responsive means for impressing undulations corresponding to said sound waves upon said 55 last mentioned oscillations.

predetermined frequency upon said last 60 mentioned oscillations, and means controlled by said second mentioned responsive means for impressing undulations corresponding to said sound waves upon said last mentioned oscillations.

65 11. The combination with transmission means including means for generating electrical oscillations of a predetermined frequency, means for simultaneously impressing regular periodic variations of a predetermined frequency and irregular undulations corresponding to sound waves upon said oscillations of a relay including receiving means comprising responsive means in resonance with said oscillations, responsive means controlled by said first 70 mentioned responsive means and in resonance with said periodic variations, means for generating electrical oscillations of a predetermined frequency different from said first mentioned frequency, means for impressing regular periodic variations of a predetermined frequency different from said second mentioned frequency upon said last mentioned oscillations, and means controlled by said second mentioned responsive means for impressing undulations corresponding to said sound waves upon said last mentioned oscillations.

75 12. The combination with transmission 80 means including means for generating electrical oscillations of a predetermined frequency, means for simultaneously impressing regular periodic amplitude variations of a predetermined frequency and irregular 95 undulations corresponding to sound waves upon said oscillations of a relay including receiving means comprising responsive means in resonance with said oscillations, responsive means controlled by said first 100 mentioned responsive means and in resonance with said periodic variations, means for generating electrical oscillations of a predetermined frequency, means for impressing regular periodic amplitude variations of a predetermined frequency upon said last mentioned oscillations, and means controlled by said second mentioned responsive means for impressing undulations corresponding to said sound waves upon said 110 last mentioned oscillations.
